UNITED STATES PATENT OFFICE

MAURICE GALLET, OF POUGHKEEPSIE, NEW YORK

AERO PROPELLING AND STEERING MEANS

Application filed November 16, 1928. Serial No. 319,771.

This invention relates to means for propelling and steering such vehicles as aeroplanes, lighter than air craft, and boats or hydroplanes, and other transporting means which 5 may be propelled by suitable devices.

The object of the invention is to provide suitable means propelling the vessel in any direction desired, such as horizontal, vertical or at any angle thereto.

10 Another object of the invention is to provide means for steering the vessel in any direction by the operation or adjustment of said propelling means.

In the operation of the above mentioned 15 types of vessels the ascent from the ground is slow and requires a large space in which to take off from or to alight on, and in the case of lighter than air vessels, they are not provided with any means whereby they can be 20 propelled along the ground, and require manual labor to accomplish this object, and further there is no means provided by which such a vessel can be turned around in a small space, 25 under any weather conditions.

25 In the combined propelling and steering means forming the subject matter of this invention, means are provided whereby an aerial vessel may be propelled along the ground, directly raised or lowered from the 30 ground, or steered in any direction, this being accomplished by a series of tubular devices mounted thereon in an adjustable manner and provided with means for propelling or sucking air therethrough.

35 With these and other objects in view, my invention consists in certain construction and combination of parts as will hereinafter be fully described and claimed and illustrated in the accompanying drawings in which like 40 figures of reference refer to corresponding parts in all of the views, but it is understood that slight changes may be made without departing from the spirit of the invention.

In the drawings:

45 Figure 1, is a side elevation of an air ship, showing my invention as applied thereto.

Figure 2, is a front elevation of the same.

Figure 3, is a detail cross sectional view of 50 one of the propelling and steering devices, showing the method of operating the same.

Figure 4, is a detail view of one of the steering devices, showing some of its various positions.

Figure 5, shows the invention as applied to 55 an aeroplane.

Figure 6, shows the invention as applied to a boat.

Referring to the drawings, there is shown in Figures 1 and 2, an air ship of the lighter than air type, but which is constructed with a 60 central longitudinal tube extending the entire length of the ship and having open ends, with one or more propellers 11 mounted therein, and adapted to propel the ship through the air by forcing air through said tube 10.

Above and partly embracing said tube 10, 65 is the gas bag 12, which is of suitable construction and designed to contain the gas with which the ship is supported, and below said tube 10 is supported the main body of the 70 ship 13, which contains the cabins, engine room, pilot house etc.; and to the lower part thereof are attached the landing wheels 14 by suitable means such as the springs 15.

To both sides of the ship 10 at suitable 75 locations, are mounted a series of adjustable tubular combined propelling and steering devices, which are adapted to be moved or swung upon their mountings, to point ahead as in flight, downward as in landing, or upward 80 as in ascending, and it will thus be seen that by the use of these devices the ship may be run straight out from a hangar upon its landing wheels, and then by pointing the devices upward the ship will be carried either 85 upward on an angle or straight up according as to the direction of the devices, and further by changing the inclination of the devices from each other the steering of the ship may be accomplished, wind resistance overcome, 90 and by reversing the rotation of the propellers which are mounted within said devices the ship may not only be made to back, but the devices can be used as a brake.

These combined propelling and steering 95 devices, comprise a tubular member 16, open on the ends and having mounted therein a propeller or other suitable device 17, which may either be operated by a motor 18 supplied with current from a central power plant 100

in the body of the ship 13, or by suitable mechanical means from said power plant, as indicated in Figure 3 by the gearing 19 and shaft 20.

5 The mounting of these cylinders or members 16, may be by any suitable means, but is here shown in Figure 3, as a swivel bracket 21 having one part attached to the member 16 and the other part attached to the ship or 10 framework thereof, and within said bracket 21 is a shaft 22 for the purpose of tilting said member 16 to any desired angle.

For the purpose of turning the ship around in a small space or to overcome the wind resistance and keep the ship on its course there is provided near the ends of the body 13 a transverse tubular member 25, similar to the members 16, but mounted in a stationary manner, but having therein a propeller 26, 20 which may be rotated in either direction, and in this manner, by rotating the propeller in the forward member 25 in one direction and the propeller in the rear member 25 in the opposite direction, the ship will turn around, 25 or by regulating the direction of rotation and speed of these propellers, the ship may be steered as desired.

It is understood that these members 16 and 25, may be of any suitable size and material 30 and may be provided if desired with cone shaped ends as indicated by 27; and also the end of the tubular member 10 may be provided with a hood 28.

Also toward the rear end of the ship and 35 partly within the tube 10 may be mounted a blade wheel 29 designed to be rotated by the air passing through the tube 10, and this wheel 29 may be used to operate generators for the purpose of creating power for lights, 40 etc.

In Figure 5 of the drawings is shown an aeroplane 30 which may be supplied with similar combined propelling and steering members 31, mounted in a tilting manner on 45 suitable supports 32, the propeller 33 therein being operated through suitable mechanism from the power plane of the aeroplane, and these members 31 may be used for propelling, raising and lowering and steering the 50 plane.

In Figure 6 of the drawings is shown a boat, and the manner of using these combined propelling and steering members 34 therewith, one being used on each side of the 55 boat, and by regulation of the speed of their propellers, steering of the boat may be effected, and by proper tilting of these members the proper trim of the boat may be effected.

It is also understood that the use of these 60 propelling and steering members is not confined to the uses as shown, but may be adapted to other vehicles, or purposes.

In the boat shown in Figure 6 the tubular combined steering and propelling member 65 34 is formed with a flanged end 35, and is sup-

ported on the supports 37 attached to the boat 41, and is adapted to be tilted thereon in some suitable manner, and the propeller 36 operated either by a motor attached direct and supplied with current from the power plant of the boat, or by suitable mechanical devices such as a vertical shaft 38 from the power plant of the boat. 70

The rear of the tube 34 may be formed with a depression 39 and have mounted therein a wind driven wheel 40 for the purpose of operating a generator or other power device, this wheel 40 being rotated by the air as it is driven through the tube. 75

Having thus described my invention, what I claim as new and desire to secure by Letters Patent, is:

1. In combination with an air ship formed with a tubular portion partly surrounded by a gas chamber, of means for propelling and steering said ship, comprising tubular members attached thereto on different planes in an adjustable manner and containing propelling means, means for turning said ship on its vertical axis, comprising a pair of tubular members mounted thereon in transverse relation to the axis thereof and provided with means for forcing air therethrough in either direction. 85

2. In combination with vessel formed with a tubular portion partly surrounding by a gas chamber, of means for propelling and steering the same, comprising tubular members adjustably secured thereto on different planes and adapted to be tilted to control the direction of travel of said vessel, and containing propelling means for actuating the movement of said vessel, and means mounted on said vessel for turning the same, comprising transverse tubular members containing propelling 90 means. 100

In testimony whereof I affix my signature.
MAURICE GALLET.
